CLAIM

We claim the ornamental design for a growler, as shown and described.

DESCRIPTION

FIG. 1 is a front perspective view of a growler, showing our new design;

FIG. 2 is a front elevation view thereof;

FIG. 3 is a rear elevation view thereof;

FIG. 4 is a left side elevation view thereof;

FIG. 5 is a right elevation view thereof;

FIG. 6 is a top plan view thereof;

FIG. 7 is a bottom plan view thereof; and,

FIG. 8 is a cross-section view thereof, taken at lines 8-8 of FIG. 4.

The broken line portions show unclaimed subject matter only and form no part of the claimed design.
